CAMP STOVE

Lester E. Daizell and Ralph C. Daizell, Flint, Mich.

Application July 14, 1938, Serial No. 219,244

7 Claims. (Cl. 126—25)

This invention relates to an improved portable cooking stove for campers.

A further object of the invention is to provide a camper's cooking stove having a top heat radiating surface for cooking and means whereby the heat and products of combustion will be drawn upwardly in the forward part of the stove, along the ends of the stove, and outwardly through the rear part of the bottom of the stove, to thereby provide a uniform heat for the entire top cooking surface.

A further object of the invention is to provide a removable grate formed of sheet metal with punched out slits forming openings therein to permit a circulation of air therethrough from an adjustable draft mechanism formed in the front part of the stove below the grate.

Still another object of the invention is to provide a stove having a casing and a partition dividing the casing into compartments, with openings at one end of the stove provided with doors, each of said openings communicating with one of the compartments and adapted to permit the storage of the sections of a stove pipe and the stove legs in said casing when said stove is in transit.

Other objects and advantages of the invention will hereinafter become more fully apparent from the following description of the drawings which illustrate a preferred form of the invention, and wherein:

Figure 1 is a side elevational view showing the stove assembled and positioned in a tent with the stove pipe connected to the stove and extending upwardly from beneath the earth beyond one side or end of the tent,

Figure 2 is a longitudinal vertical sectional view taken on the lines 2—2 of Figure 1,

Figure 3 is a view similar to Figure 2 taken on the lines 3—3 of Figure 1,

Figure 4 is a transverse sectional view taken on the lines 4—4 of Figure 2,

Figure 5 is a horizontal sectional view taken on the lines 5—5 of Figure 2,

Figure 6 is a fragmentary elevational view showing the draft opening,

Figure 7 is a horizontal sectional view taken on the lines 7—7 of Figure 6, and

Figure 8 is a horizontal sectional view taken on the lines 8—8 of Figure 2, and shown on an enlarged scale.

Referring more particularly to the drawings wherein like reference characters designate like or corresponding parts throughout the different views, 10 designates generally the stove, 11 a con-

ventional tent, as seen in dotted lines, and 12 the earth's surface or ground level.

The stove designated generally 10, includes the casing preferably formed of sheet metal, and comprising the top 13, end walls 14 and 15, bottom sections 16 and 17, rear wall 18 and front wall 19. These portions are preferably connected by means of the joints 20 which are preferably in the form of the portions 21 which are turned back upon themselves to clamp the flanges 22, but any other suitable form of joint may be substituted for the joint 20 if desired.

A partition 23 extends upwardly from between the bottom sections 16 and 17, and extends the length of the stove 10 with its opposite ends 24 projecting through the slots 25 formed by the adjacent sections of the end walls 15 and 16 which are bent outwardly upon themselves as seen at 26 in Figure 3. Clamps 27 which are provided with the inturned longitudinal edges to engage the portion 28, removably retain the sections of the ends 14 and 15 in clamping engagement with the angular shaped ends 24 of partition 23. The bottom edge of partition 23 projects downwardly between the downturned flanges 28 of the bottom sections 16 and 17, and is provided with the tongues 29 which are bent outwardly and upwardly, alternately in opposite directions to clamp the bottom of the partition 23 to the adjacent edges of the sections 16 and 17, as best seen in Figures 2 and 4. Partition 23 adjacent its upper end, is bent rearwardly along the line 30 and the portion 31 of partition 23 above the line 30 converges sharply to a point at 32 where it contacts the joint 20 of the back 18 and top 13 of the stove 10, to form the inwardly converging corresponding openings 33 between the front compartment 34 and rear compartment 35 of the stove, which are formed by partition 23.

End sections 15 of the compartments 34 and 35 are provided with the openings 36 and 37 respectively, the opening 36, which is the larger of the two, being closed by a door 38, and the opening 37 being closed by the door 39. Doors 38 are each formed of the inner and outer spaced walls 40 and 41 respectively forming the air chambers 42 therebetween to provide heat insulating means to keep the outer walls 41 relatively cool when the stove 10 is in use. Door 38 is provided with the openings 43 in its outer wall 41 through which air may circulate through its cooling space 42. As best seen in Figure 1, door 38 is vertically hinged at 44 and while the door 39 is horizontally hinged at its top at 45, so that the weight of the door 39 will normally re-

tain it in a closed position. Door 38 on the other hand, is provided with a pivoted latch 46 having a handle 47 and adapted to engage a stationary keeper 48 on the end wall 15 to retain it in a closed position.

A sheet metal plate 49 having the two downturned sides and the downturned back end 50, is positioned horizontally in compartment 34 adjacent its bottom 16 and is held therein by the brackets 51, which comprise strips of metal extending the length of the partition 23, and the front 19 and the width of the front section of the end wall 14, and which are secured along their lower edges by suitable fastening means, and have their upper edges 52 offset inwardly to receive the downturned flanges 50 to removably retain plate 49 therein. Plate 49 substantially divides compartment 34 to form the fire box in the upper part of said compartment, and the ash pit beneath plate 49. As best seen in Figures 2 and 5, plate 49 is provided with a plurality of transverse spaced slits the opposite edges of which are bent downwardly to form the slots 53, thereby forming the inverted U-shaped bars 54 between the slots 53 to convert the plate 49 into a removable grate. Front wall 19 as best seen in Figure 6, is provided with a plurality of spaced openings 55 which communicate with the ash pit beneath the grate 49, and the bracket 51 which is secured to wall 19 is provided with an offset lower edge 56 corresponding to the upper offset portion 52 to cooperate with a bracket 57 corresponding to the brackets 51 to form a guideway for a plate 58 which is slidably mounted on the inner side of wall 19. Plate 58 is provided with a plurality of spaced openings 59 which are adapted to align with openings 55, and with a handle 60 which projects outwardly through one of the openings 55 and by means of which plate 58 may be moved relatively to the wall 19 to close or partially close the openings 55. It will thus be seen that an adjustable up-draft is provided whereby air may be admitted from without into the bottom of compartment 34 to pass upwardly through the slots 53 to provide a draft for the fire in the upper part of compartment 34.

Stove 10 at its four bottom corners is provided with the removable legs 61 formed of angle iron, which are suitably secured to the bottom corners of the stove by any suitable means not shown, to elevate the stove from the ground 12.

As heretofore mentioned, and as best illustrated in Figure 1, the stove 10 is constructed as a portable camper's stove and is particularly adapted for use in tents. As seen in Figure 3, bottom section 17 of compartment 35 is provided with an opening 62 into which is fitted an end 63 of a stove pipe, designated generally 64, which has an intermediate portion 65 positioned below the earth's surface 12 and an upwardly extending opposite end 66 through which the smoke and other products of combustion from the stove 10 is expelled. Intermediate portion 64 which is disposed beneath the ground and which extends away from the stove 10, permits the end 66 to extend upwardly on the outside of the tent 11, as best seen in Figure 1, so that no opening need be made in tent 11 to accommodate the pipe 64. Pipe 64 comprises a plurality of pipe sections 67 and the two elbows 68 which are adapted to be disassembled for transportation, and stored in compartments 34 and 35 together with the legs 61 thereby forming a compact assembly for transportation.

From the foregoing it will be seen, that the

door 38 may be opened to build a fire on the top of the grate 49 and for the purpose of feeding the fire and removing the ashes from the bottom of compartment 34, and the draft for the fire may be controlled by adjusting the draft plate 58. Air will be drawn in through openings 55 and 59, upwardly through slots 53 to convey the heat and products of combustion from the fire not shown, upwardly through openings 33 into compartment 35, downwardly through end 63, 10 through the subterranean portion 65 and upwardly through end 66 to be expelled beyond the tent 11. The entire top 13 of the stove 10 is adapted to be used for cooking, and the converging portion 31 directs the heat as well as the products of combustion toward the opposite ends of top 13 so that substantially the entire top surface of the stove will be subjected to a uniform heat. Pipe sections 67, elbows 68 and legs 61 are inserted through the openings 36 and 37 in the section of the end wall 15 for storage and transportation.

Various modifications and changes in the construction and arrangement of the parts forming the invention may obviously be made and are contemplated, as the drawings and description are only intended to illustrate a preferred form of the invention, and the right is reserved to make such variations and changes as do not depart from the spirit and scope of the invention as hereinafter defined by the appended claims.

We claim as our invention:—

1. A device of the class described comprising a cooking stove having a vertical partition dividing it into front and rear compartments, said front compartment having a grate spaced from its bottom, draft means formed in the front of said stove and beneath said grate, portions of the upper edge of said partition being spaced from the top of the stove to provide openings through which the smoke and products of combustion may pass from the front to the rear compartment of the stove.

2. In a portable camper's cook stove, a hollow body portion having a wall disposed interiorly thereof to divide the stove into front and rear compartments, the upper end of said wall being bent rearwardly and being tapered to provide communicating openings between the ends of said compartments, said front compartment comprising the fire box and being provided with a grate extending the length and width thereof and in spaced relationship to the stove bottom, an adjustable draft formed in the front of said stove beneath said grate.

3. In a portable camping stove, a stove body formed of sheet metal or the like and provided with a vertical partition forming front and rear compartments, the upper end of said partition being inclined rearwardly and converging to form communicating openings at the ends of said compartments, said front compartment forming the fire box and being provided with a horizontal grate formed of sheet metal having transverse slots, the front wall of said stove being provided with a plurality of openings beneath said grate, and a plate slidably mounted behind said openings and provided with openings to align with said first mentioned openings to form a draft.

4. A device as in claim 3, said stove being provided with openings at one end thereof communicating with said compartments, and doors mounted to normally close said openings, each of said doors having spaced outer and inner walls forming an air space therebetween.

5. In a camper's cook stove, a hollow body portion having a transverse partition provided with openings at its upper end extending from the ends of the stove and converging at its center, and said front compartment forming the fire box and being provided with a horizontal grate and draft means in the front part of said stove and beneath said grate.
6. In a camper's cook stove, a stove adapted to be positioned in a tent and provided with a flat cooking top, a partition dividing said stove into front and rear compartments and having an upper end bent rearwardly and converging at the back end of said stove to form communicating openings at the ends of said compartments, said upper end forming a tapered upwardly inclined baffle for directing the heated products of combustion against the top of the stove, said front compartment comprising the
- fire box and being provided with a grate, and adjustable draft means communicating with said compartment beneath said grate.
7. In a portable camper's cooking stove, a stove body having a top forming a heat radiating surface, a partition positioned transversely in said stove and having a rearwardly inclined converging upper end dividing the stove into front and rear compartments, said front compartment forming the fire box and having a grate and draft means positioned beneath said grate, and having a smoke outlet co-acting with said rear compartment, said draft means for causing the products of combustion to be drawn upwardly against the top plate of the stove and over the ends of said partition to provide a substantially uniform heat for the stove top.
